UNITED STATES PATENT OFFICE.

JOHN H. WEARE AND NATHAN WEARE, OF CINCINNATI, OHIO, ASSIGNORS
OF ONE-FOURTH THEIR RIGHT TO GEORGE W. BISHOP, OF SAME PLACE.

IMPROVEMENT IN CULINARY VESSELS.

Specification forming part of Letters Patent No. 158,155, dated December 22, 1874; application filed December 3, 1874.

To all whom it may concern:

Be it known that we, JOHN H. WEARE and NATHAN WEARE, both of Cincinnati, Hamilton county, State of Ohio, have invented a certain new and useful Improvement in Culinary Vessels, of which the following is a specification:

Our invention is designed as an improvement upon the culinary vessel for which Letters Patent No. 154,305 were issued to us August 18, 1874; and consists of a peculiar device for connecting the detachable plate to the body of the vessel, by which easy, inexpensive molding is provided for, and a firm fastening obtained.

Figure 1 is a perspective view of a cooking-pot for stove purposes, embodying our present improvement, the cover or lid of the vessel being removed to expose the interior. Fig. 2 is a detached perspective view of the parts embracing the improved fastening. Fig. 3 is a section, showing a modification in the construction of the fastening for the upper end of the detachable plate.

A is the body of the vessel; B, the vapor-duct; C, the lifting-bail; and D, the dumping-bail. The lid or cover necessary for the vessel, to render the vapor-duct B operative for carrying off the vapors arising from the boiling liquids into the stove, is removed in order to expose the construction of the fastening for the detachable plate E. At the bottom of the vapor-duct and on each side of it a groove, a, is molded and formed in the vessel, as shown, and the bottom of the detachable plate E is provided with a projecting lug, e, on each side to match and fit into the grooves a. The lugs are inserted in the grooves by an entry of the same at the bottom and a sliding motion of the plate E upward. This form of fastening for the bottom of the plate E, while it is perfectly firm in the support of the plate E, gives every facility for molding without coring, and without difficulty in withdrawing the pattern from the mold.

At the top of the duct I project from the

body of the vessel a stud, F, which I prefer should extend entirely through the plate E, as shown in Fig. 1, so that a small nail or pin, f, through it outside of the plate, will suffice to secure the plate at this point. But, as a modification of this, the projection F may be shorter, and the pin f may be inserted underneath it, as shown in Fig. 3, the upper edge e' of the plate, in this case, being dovetailed into the top of the vessel, the grooves a being necessarily of sufficient length to enable the plate to move upward until the dovetail rim is in place for lowering into the dovetail recesses in the top of the vessel. After such lowering into place the pin f is inserted to prevent the plate from rising, the lugs e still remaining in the grooves. The indentations c, when the lid of the vessel is on, supply air for cooling off the cover, by traversing under it, and act to keep up the draft into the duct B. The apertures b at the top of the plate are fully shown and described in our previous patent, heretofore referred to.

The bail-ears d are formed to project from the side of plate E, and come in contact (when the plate E is in place) with the periphery of the vessel A. This formation gives an open ear for the insertion of the bail when the slide is out, and enables the ears to be molded and cast without coring.

We claim—

1. In combination, with the vessel A, having detachable slide or plate E to complete the vapor-duct B, the projection F, pin f, lugs e, and grooves a, operating substantially as and for the purpose described.

2. The combination of vessel A, plate E, dumping-bail D, and projecting open bail-ears d, substantially as and for the purpose stated.

In testimony of which invention we hereunto set our hands.

JOHN H. WEARE.
NATHAN WEARE.
